UNITED STATES PATENT OFFICE.

CHARLES R. WHITMAN, OF CHICAGO, ILLINOIS.

COLLAR ATTACHMENT.

1,079,085.

Specification of Letters Patent. Patented Nov. 18, 1913.

Application filed August 5, 1911. Serial No. 642,554.

To all whom it may concern:

Be it known that I, CHARLES R. WHITMAN, a citizen of the United States, residing at Chicago, in the county of Cook and 5 State of Illinois, have invented a certain new and useful Improvement in Collar Attachments, of which the following is a specification.

My invention relates to improvements in 10 collar adjusting and holding attachments, and has for one object to provide means for holding together in their normal positions the open ends of the outer portion of the usual type of turnover or roll collar.

15 It is illustrated diagrammatically in one form in the accompanying drawing, wherein—

Figure 1 is a perspective view of the collar with the device in position. Fig. 2 is a perspective view of the same collar without the 20 device. Fig. 3 is an elevation of the device. Fig. 4 is a plan view of the device.

Like parts are indicated by like letters in the drawing.

25 My device consists of a substantially U shaped portion made up of the two vertical prongs A A connected at one end by the member A¹, from which project the two downwardly extending parts to form the 30 collar button engaging lugs A². The prongs A support at the upper outer ends the inclined arms A³, which are slightly curved horizontally and vertically to meet the prongs A as indicated at A⁴ and in Fig. 4 35 and terminate in the slightly curved end portions A⁵. The connecting members A¹ A¹ and the arms A³ are slightly bent or curved to conform more closely to the contour of the neck and collar. As indicated in the drawing, the device is used in connection with a 40 collar in the following manner.

The collar B is first adjusted in position, being held by the usual collar button B¹. The arms A³ are then inserted beneath the 45 folds of the collar, and the lower connecting portion A¹ of the U-shaped frame is pressed upwardly until it reaches a sufficient height to permit the lugs A² to pass over the head of the collar button when they 50 spring down and engage the opposite sides of the shank. During this movement it will be understood that the arms A³, pressing

the inner upper portions of the folds of the collar, spread sidewise to permit upward movement of the connecting part above the 55 collar button, before the connecting part springs down against the button. The arms A³ are then left in position beneath the fold of the collar and their presence in opposition to it tends to hold the collar to its normal 60 position, preventing its sagging at the sides and tending to hold the meeting ends of the folded portions together in the normal position.

It is obvious that the device will have to 65 be of different sizes in collars of different widths. The real object of the device is to hold the parts of the collar in their normal position, or where they tend to get out of or sag from their normal positions to restrain 70 them from so doing, and the action of the device is by engagement with the inner surface of the roll to counteract the tendency of the parts to separate or sag in front.

The inwardly curved ends make the removal and application of the device easier. 75 The curvature of the prongs and the arms, particularly the latter, is such as to conform to the normal shape of the collar, and the arms are of such shape as to engage the inner 80 edge of the roll for a considerable portion of its length, thus obviating the disadvantages of a one point contact, and frictional contact between the collar and these arms will prevent the collar from slipping or being 85 displaced.

The device is made of strong metal, and its height for any given collar such that it is held yieldingly between the top of the collar and the collar button, though no great degree of elasticity is necessary for this purpose and a non-elastic device could be forced 90 into position.

It is evident from the foregoing description and the drawing, that the parts A³ of 95 the device will press against the collar along the inner edge of the fold whenever the collar sags, and that the resistance of these parts of the device increases in proportion to the tendency to sag, thus preventing displacement of the collar and holding it in position without wrinkling or distortion.

I claim:
A supporting means for turnover collars

comprising a wire U-shaped frame having normally parallel spring arms, a spring cross member connecting said arms and intended to engage the collar button, outwardly extending spring fingers projecting from the free ends of the arms in opposite directions, said fingers being substantially parallel with the fold of the collar when in

position, curved at either end, and adapted to engage and underlie the fold of the collar to hold it in position.

CHARLES R. WHITMAN.
